Primary Examiner — Darlington Ly

(74) Attorney, Agent, or Firm — Adams Grumbles, LLP;
Brittany Nanzig(57) **CLAIM**

The ornamental design for an air impact wrench, as shown and described.

DESCRIPTION

The file of this patent contains at least one photograph executed in color. Copies of this patent with color photographs will be provided by the Office upon request and payment of the necessary fee.

FIG. 1 is a right side elevational view of an air impact wrench showing my new design.

FIG. 2 is a left side elevational view of the air impact wrench.

FIG. 3 is a rear elevational view of the air impact wrench.

FIG. 4 is a top plan of the air impact wrench.

FIG. 5 is a bottom plan view of the air impact wrench.

FIG. 6 is a right side perspective view of the air impact wrench.

FIG. 7 is a rear perspective view of the air impact wrench; and,

FIG. 8 is a bottom perspective view of the air impact wrench.
